Des. 185,865

Patented Aug. 11, 1959

185,865

FISHING LURE

Clyde A. Herman, Fond du Lac, Wis.

Application March 16, 1959, Serial No. 55,003

Term of patent 14 years

(Cl. D31—4)

Fig. 1.

Fig. 2.

Fig. 3.

Fig. 1 is a right side view, slightly in perspective, of a fishing lure showing my new design, the left side being substantially like the right side shown;

Fig. 2 is a top plan view thereof; and

Fig. 3 is a bottom plan view thereof.

I claim:

The ornamental design for a fishing lure, substantially as shown and described.
